(57) **CLAIM**

The ornamental design for a document processing device, as shown and described.

DESCRIPTION

FIG. 1 is a front perspective view of a document processing device showing our new design;

FIG. 2 is a rear perspective view of the document processing device shown in FIG. 1;

FIG. 3 is a front elevational view of the document processing device shown in FIG. 1;

FIG. 4 is a top plan view of the document processing device shown in FIG. 1;

FIG. 5 is a right side view of the document processing device shown in FIG. 1;

FIG. 6 is a left side view of the document processing device shown in FIG. 1; and,

FIG. 7 is a back elevational view of the document processing device shown in FIG. 1.

The broken lines are included for the purpose of illustrating the base and defining boundaries in the upper portions and form no part of the claimed design.
